CORNER-POSITIONABLE HEATER CASING

Jordan L. Heiman, St. Louis, Mo.

Application July 6, 1949, Serial No. 3,728

Term of patent 14 years

(Cl. D81—19)

To all whom it may concern:

Be it known that I, Jordan L. Heiman, a citizen of the United States, and a resident of the city of St. Louis, in the State of Missouri, have invented a new, original, and ornamental Design for a Corner-Positionable Heater Casing, of which the following is a specification, reference being had to the accompanying drawing, forming part thereof.

In the drawing:

Figure 1 is a perspective view of the corner-positionable heater casing as viewed from a front corner, showing my new design; and

Figure 2 is a similar view of the same on a reduced scale, as viewed from the diagonally opposite rear corner.

I claim:

The ornamental design for a corner-positionable heater casing, as shown.

JORDAN L. HEIMAN.
